UNITED STATES PATENT OFFICE

HENRY F. QUICKEL, OF HARRISBURG, PENNSYLVANIA.

FURNACE-REGULATOR.

1,104,311.

Specification of Letters Patent. Patented July 21, 1914.

Application filed November 5, 1912. Serial No. 729,620.

To all whom it may concern:

Be it known that I, HENRY F. QUICKEL, a citizen of the United States, residing at Harrisburg, in the county of Dauphin and State of Pennsylvania, have invented or discovered certain new and useful Improvements in Furnace-Regulators, of which the following is a specification, reference being had therein to the accompanying drawings.

10 This invention relates to draft regulating mechanism for furnaces and is more particularly designed for use in connection with steam boiler furnaces for steam heating for the purpose of regulating the pressure in the boiler, although the invention is not to be considered as limited to this use.

One object of the invention is to provide improved regulating mechanism which will positively and automatically control the pressure in the boiler or the like irrespective of exterior atmospheric conditions, which mechanism will be reliable but delicate in its operation and therefore peculiarly adapted for use in connection with vapor or low pressure steam systems.

Another object of the invention is to provide improved means whereby the normal pressure automatically maintained may be conveniently adjusted or varied.

30 These and other objects of the invention, together with means whereby the same may be carried into effect, will best be understood from the following description of one form or embodiment thereof illustrated in 35 the accompanying drawing. It is to be understood, however, that the construction shown has been chosen for illustrative purposes merely, and that the invention may be embodied in other forms without departing

40 from the spirit and scope thereof.

The said drawing illustrates, in diagrammatic elevation, partly broken away, a furnace provided with a controlling system arranged in accordance with the invention.

45 12 denotes a steam boiler and 13 the furnace for heating said boiler, said furnace being provided with the usual ash-pit door having an air intake damper 15 and with a smoke pipe 16 within which is a cut-off 50 damper 17. The damper 17 is pivoted within the smoke pipe 16 by being secured to a spindle 18 which passes loosely through openings in the smoke pipe and is provided outside of said pipe with an arm 19 to which

55 is secured one end of a chain or other flexible connector 21. The chain or connector 21

passes over one or more pulleys 22 suitably supported, as by the ceiling of the furnace room, and is secured at its opposite end to the damper 15. By this arrangement the opening and closing movements of the dampers are in unison, *i. e.* when one is opening the other will be opening also, and vice versa, but the length of the chain 21 is such as to permit the damper 15 to be brought to rest in closed position without completely closing the damper 17.

23 denotes one or more counterweights carried by the chain 21 at a point removed from said damper 15 and between it and the pulley or pulleys 22. The damper 15, in the construction shown, is so hung as to tend normally to close by gravity. The damper 17, on the other hand, by reason of the position of the arm 19 which may, if necessary, be suitably weighted for this purpose, will normally open by gravity. After the damper 15 has fully closed the weight 23, when permitted by the controlling mechanism hereinafter more fully described, will close the damper 17 against the weight of the arm 19.

The mechanism whereby the dampers are controlled by the boiler pressure may be of any suitable character, but for convenience is herein shown as of the type disclosed and claimed in Letters Patent No. 1,045,610, granted to me Nov. 26, 1912. Said controlling mechanism comprises a float chamber 24 communicating through pipes 26 and 27 with the bottom of the boiler 12. The arrangement is such that, the water level in the boiler remaining constant, the level in the chamber 24 will vary in accordance with the vapor pressure in the boiler.

28 denotes a float within the chamber 24. Attached at one end to the float 28 is a chain or other flexible connector 33 which passes over a pair of pulleys 34—34, and such additional pulleys 35 as may be necessary in accordance with the arrangement of the apparatus, said pulleys being suitably supported, as from the ceiling of the furnace room. The opposite end of the chain or connector 33 is attached, as at 36, to the chain or connector 21.

The float chamber 24 is preferably so located with respect to the boiler 12 that when the water in the boiler is at its normal level and there is no steam pressure in said boiler the float 28 will stand at substantially its lowest point. The connections

are such that at this time the dampers 15 and 17 are both wide open, the weight of the float 28 being sufficient to counterbalance the weight or weights 23 and the resistance of said dampers 15 and 17. As the pressure in the boiler rises the float rises in the float chamber, permitting the dampers gradually to close. When the damper 15 is fully closed the cut-off damper 17 will still remain slightly open, as is usually desirable, particularly when fresh coal has recently been applied to the fire. The draft is now substantially fully checked so far as is necessary under normal conditions. 10

15 Should a high wind, however, prevail outside, so that the pressure in the boiler continues to rise, it is desirable that the damper 17 be fully closed. This is automatically accomplished in the present apparatus by 20 the further rise of the float 28 which permits the weight 23 to fully close the damper 17 after the damper 15 has been brought to rest in closed position, as above described. When the boiler pressure falls, the float 28 25 descends and causes, first, the opening of the damper 17, and then the opening of both dampers 15 and 17, the operation being substantially the reverse of that above described. It will thus be seen that the dampers, and consequently the draft of the furnace, are automatically controlled so as to 30 keep the boiler at a substantially constant normal pressure. In order to vary or adjust this normal pressure in accordance with the requirements the following means are provided.

Intermediate the pulleys 34 the chain or connector 33 passes about or carries a pulley 50 from which is suspended a weight 51. 40 Said weight 51 is sufficient to overcome or counterbalance the weight 23 together with the weight of the damper 15, but is lighter than the float 28 and consequently has no influence on the position of the latter. By 45 adjusting the position of the pulley 50 the chain or connector 33 is flexed more or less, and the effective length thereof varied.

For adjustably supporting the pulley 50 and weight 51 there is secured to said pulley 50 a chain or other flexible connector 52 which preferably passes over one or more pulleys 53 in accordance with the desired arrangement of the apparatus, said pulleys being suitably supported, as from the ceiling of the furnace room. Means are provided whereby the opposite end of the connector 52 may be secured at any one of a plurality of fixed points. To this end, in the construction shown, the following means are 55 provided.

54 denotes a suitable support provided with a series of pins or knobs 55. The support 54 may be located in the furnace room or at any other convenient point on the same floor or upon one of the floors above.

The chain 52 passes through a fixed guide 56 secured to the support 54 and is provided adjacent its end with a ring or loop 57 which may be engaged with any one of the pins 55, as by means of an operating handle 58. 70

59 denotes a hook or other stop carried by the chain 52, said stop coöperating with the guide 56 to limit the movement of the chain 52 and consequently the amount of flexure of the chain 33 should the ring 57 become accidentally disengaged from any of the pins 55.

With the arrangement shown, in order to increase the normal pressure of the boiler, the ring 57 is engaged with a pin 55 higher in the series. This causes the weight 51 to descend, increasing the flexure of the chain 33 and decreasing the effective length thereof, so that a greater rise of the float is required in order to produce the same effect upon the dampers. In order to decrease the normal boiler pressure the ring 57 is engaged with a pin 55 lower in the series. It will be obvious that the support 54, particularly if located upon a floor above the furnace room, may be so arranged that the above operations for increasing or decreasing the normal pressure should be reversed, that is to say, in order to increase the pressure the ring 57 might be engaged with a pin 55 lower in the series, and vice versa. 90

While the controlling mechanism has been described as being in communication with a boiler, which would be the case were the apparatus used for regulating a steam boiler furnace, as in a steam heating system, this apparatus has been found to be equally useful in connection with hot water heating systems. When so used the float chamber is located at the highest part of the system, and the rise and fall of the level of the water therein is caused by expansion and contraction of the water in the system due to changes in temperature. Where, therefore, I have herein, for convenience, employed the term "boiler", I intend by this term to comprehend corresponding and equivalent containers of hot water and other heating media in which the water or other fluid is heated, although not to the boiling point. 105

It will also be understood that the utility of the apparatus is not limited to heating systems, but that it may be equally useful for regulating any furnace to which its various features are applicable. 110

Having thus described my invention, I claim:

1. The combination with a furnace having a smoke pipe, a normally open cut-off damper in said smoke pipe, a normally closed air intake damper, and controlling mechanism for said dampers, of means connecting said dampers whereby both the 120 125 130

opening and the closing movements thereof are in unison, said means being adapted to permit said cut-off damper to remain partly open when said air intake damper is brought 5 to rest in closed position, and automatically acting means for thereafter fully closing said cut-off damper when permitted by said controlling mechanism.

2. The combination with a furnace having 10 a smoke pipe, a cut-off damper in said smoke pipe opened by gravity, an air intake damper closed by gravity, and controlling mechanism for said dampers, of a flexible connector connecting said dampers, a pulley 15 over which said connector passes, means connecting said controlling mechanism with said flexible connector, said connector being arranged to cause both the opening and the closing movements of said dampers to be in 20 unison but being of a length to permit said cut-off damper to remain partly open when said air intake damper is brought to rest in closed position, and a counterweight carried by said connector at a point removed from 25 said air intake damper and between the same and said pulley for closing said cut-off damper independently of said intake damper.

3. The combination with a furnace having 30 one or more dampers, of mechanism for controlling said dampers, a flexible connector connecting said dampers and controlling mechanism, means for supporting said connector, and adjustable means for flexing 35 said connector to vary the effective length thereof.

4. The combination with a furnace having 40 a pair of dampers, of a flexible connector connecting said dampers, one or more pulleys over which said connector passes, mechanism for controlling said dampers, a second flexible connector connecting said first named connector and said controlling mechanism, and adjustable means for flexing 45 said last named connector to vary the effective length thereof.

5. The combination with a furnace having 50 one or more dampers, of mechanism for controlling said dampers, a flexible connector connecting said dampers and controlling mechanism, means for supporting said connector, and a separate adjustable pulley over which said connector passes for flexing the same to vary the effective length thereof.

55 6. The combination with a furnace having one or more dampers, of mechanism for controlling said dampers, a flexible connector connecting said dampers and controlling mechanism, a pair of pulleys over which 60 said connector passes, a third pulley intermediate said first named pulleys, and means for adjusting said last named pulley.

7. The combination with a furnace having 65 one or more dampers, of mechanism for controlling said dampers, a flexible connec-

tor connecting said dampers and controlling mechanism, a weight carried by said connector, and adjustable means for supporting said weight.

8. The combination with a furnace having 70 a smoke pipe, a normally open cut-off damper in said smoke pipe, a normally closed intake damper, and controlling mechanism for said dampers, of means connecting said dampers whereby the opening 75 and closing movements thereof are in unison, said means being adapted to permit said cut-off damper to remain partly open when said air intake damper is brought to rest in closed position, means for thereafter fully closing said cut-off damper when permitted by said controlling mechanism, a flexible connector connecting said first-named connecting means with said controlling mechanism, and adjustable means for flexing 80 said last named connector to vary the effective length thereof.

9. The combination with a furnace having 85 one or more dampers, of mechanism for controlling said dampers, a flexible connector connecting said dampers and controlling mechanism, a pulley over which said connector passes, a weight carried by said pulley, and adjustable means for supporting 90 said pulley.

10. The combination with a furnace having 95 one or more dampers, of mechanism for controlling said dampers, a flexible connector connecting said dampers and controlling mechanism, a weight carried by said connector, a second flexible connector operatively connected at one end to said weight, and means whereby the opposite end of said connector may be secured at a plurality of 100 fixed points.

11. The combination with a furnace having 105 one or more dampers, of mechanism for controlling said dampers, a flexible connector connecting said dampers and controlling mechanism, adjustable means for flexing 110 said connector to vary the effective length thereof, and means to limit the amount of said flexure.

12. The combination with a furnace having 115 one or more dampers, of mechanism for controlling said dampers, a flexible connector connecting said dampers and controlling mechanism, a weight carried by said connector, a second flexible connector operatively connected at one end to said weight, 120 a fixed guide through which said last named connector passes, and a stop carried by said last named connector and coöperating with said guide to limit the movement of said connector.

13. The combination with a furnace having 125 one or more dampers, of mechanism for controlling said dampers, a flexible connector connecting said dampers and controlling mechanism, and adjustable means for 130

flexing said connector to vary the effective length thereof, said means including a second flexible connector and means whereby the end of said last named connector may be secured at a plurality of fixed points.

14. The combination with a furnace having one or more dampers, of mechanism for controlling said dampers, a flexible connector connecting said dampers and controlling mechanism, a pair of pulleys over which said connector passes, a third pulley intermediate said first named pulleys, a weight carried by said last named pulley, a second flexible connector secured at one end to said last named pulley, and means whereby the opposite end of said last named connector may be secured at a plurality of fixed points.

15. The combination with a furnace having one or more dampers, of mechanism for controlling said dampers, a flexible connector connecting said dampers and controlling mechanism, means for supporting said connector, means for flexing said connector to vary the effective length thereof, and adjustable means for controlling said flexing means.

16. The combination with a furnace having a pair of dampers, of a flexible connector connecting said dampers, one or more pulleys over which said connector passes, mechanism for controlling said dampers, a

second flexible connector connecting said first-named connector and said controlling mechanism, a pair of pulleys over which said last-named connector passes, a third pulley carried by said last-named connector intermediate said last-named pulleys, a weight carried by said third pulley, and adjustable means for supporting said weight.

17. The combination with a furnace having a smoke pipe, a normally open cut-off damper in said smoke pipe, a normally closed air intake damper, and controlling mechanism for said dampers, of means connecting said dampers with each other whereby the opening and closing movements thereof are in unison, said means being adapted to permit said cut-off damper to remain partly open when said air intake damper is brought to rest in closed position, means for thereafter fully closing said cut-off damper when permitted by said controlling mechanism, and adjustable means connecting said first-named connecting means with said controlling mechanism.

In testimony whereof I affix my signature in presence of two witnesses.

HENRY F. QUICKEL.
